(57) **CLAIM**

The ornamental design for a three curved vane hydrotherapy jet escutcheon, as shown and described.

DESCRIPTION

FIG. 1 is a perspective view of the three curved vane hydrotherapy jet escutcheon.

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken line showing of parts of the drawings is included for the purpose of illustrating use and environment and forms no part of the claimed design.
